REFORMING MACHINE

Howard B. Peterson, San Francisco, Calif., assignee to American Can Company, New York, N. Y., a corporation of New Jersey

Application January 3, 1946, Serial No. 638,856

10 Claims. (Cl. 153—32)

1 The present invention relates to can body reforming machines and has particular reference to devices for ironing out the closely curled opposed edges or curved connecting parts, called "eyes" of collapsed partially opened can bodies as an incident to the complete reforming of such can bodies into a desired shape.

In a pending application, Ser. No. 638,854, filed January 3, 1946 by Samuel S. Jacobs and myself as joint inventors, now Patent No. 2,460,293, granted February 1, 1949, there is shown a reforming machine in which my device may be used in the manner there illustrated. No claim is made herein to the machine claimed in said pending application.

Shipment and storage of empty sheet metal can bodies for use in making containers or cans for food products sometimes is facilitated by flattening or collapsing the bodies so that they occupy less space. When ready for use, the walls of the collapsed bodies are opened or spread apart and then the bodies are reformed by rolling or other means to restore them to their original or other desired cross sectional form.

The opening of a body usually leaves a pair of oppositely disposed corrugations or curved connecting parts, known in the can making industry as eyes, in the body wall where the wall has been closely curled or bent during the collapsing operation. For best results in reforming a body these eyes must be entirely eliminated and it is to this feature that the instant invention is directed.

The invention contemplates the provision of a continuously operating ironing device in which the can body to be reformed is maintained in a non-rotating position while it is moved through a reforming station at which the eyes or curved connecting parts of the body are ironed out to restore the body to its original shape.

An object of the invention is the provision of an ironing device for a can body reforming machine wherein a can body to be reformed is continuously moved, while being held against rotation, through a reforming station at which the areas of the body which include the eyes, are ironed out to eliminate the eyes or curved connecting parts and thereby restore the body to its original shape.

Another object is the provision of such an ironing device wherein a permanent set is given the areas of the body which include the eyes, by ironing out the material of the body at these areas to an extent beyond its elastic limit so that any

set to the eyes or curved connecting parts will be permanently eliminated.

Another object is the provision of an ironing device of this character wherein the ironing out of the eyes is effected by the passage of the body between ironing elements located on opposite sides of the moving non-rotating body so that both eyes or curved connecting parts of the body can be operated upon simultaneously.

10 Another object is the provision of such an ironing device wherein the ironing action is brought about by rollers having a generated contour, shaped to progressively engage and iron out the eye areas or curved connecting parts of the bodies being reformed.

20 Numerous other objects and advantages of the invention will be apparent as it is better understood from the following description, which, taken in connection with the accompanying drawings, discloses a preferred embodiment thereof.

Referring to the drawings:

Figure 1 is a front elevation of a can body eye ironing device embodying the instant invention, with parts broken away and parts in section;

Fig. 2 is a top plan view of the device illustrated in Fig. 1, with parts broken away;

Fig. 3 is a sectional view taken substantially along the line 3—3 in Fig. 2;

30 Fig. 4 is a fragmentary rear elevation of the device shown in Fig. 1, with parts broken away;

Figs. 5 and 6 are enlarged perspective views of a can body before and after the eye ironing out operation effected by the device shown in Fig. 1; and

Figs. 7 to 12 inclusive are diagrammatic views illustrating the action of the ironing elements of the device on the can bodies.

As a preferred embodiment of the invention the drawings illustrate an ironing device for ironing out corrugations or eyes or curved connecting parts A (Fig. 5) in partially reformed or opened sheet metal can bodies B as an incident to reforming or restoring a collapsed can body to its original cross sectional form, as for example, the fully reformed cylindrical can body D shown in Fig. 6.

The opened partially reformed can bodies B are positioned, manually or in any other suitable manner, onto non-rotatable cylindrical mandrels or supports 21 (Figs. 1 and 3) which extend horizontally from a vertically disposed rotatable carrier disc 22. The disc is mounted on a horizontal drive shaft 23 journaled in bearings 24 formed in a frame 25 which constitutes the main

frame of the device. The drive shaft is continuously rotated in any suitable manner.

There are a plurality of the mandrels 21 and they are arranged in spaced and parallel order in a circle concentric with the drive shaft 23. Each mandrel is formed with a shank 27 of smaller diameter than the mandrel and this shank extends through the carrier disc 22 and is locked in place by a nut 28 which holds the mandrel stationary relative to the disc. Each mandrel is formed with a pair of oppositely disposed recessed surfaces such as flats 31 which are perpendicular to a radial line $x-x$ (Fig. 1) extending through the center of the mandrel and through the center of the drive shaft 23.

Thus when a partially formed can body B is placed on a mandrel 21 it is in a horizontal position with its side walls spread apart and frictionally engaging the mandrel, as best shown in Fig. 1. The mandrel is slightly smaller in diameter than the inside diameter of the finished reformed body and the eyes A of the body extend outwardly. The body is placed on the mandrel with these eyes or curved connecting parts at the flats 31 of the mandrels.

With a partially reformed body B on its mandrel 21, the continuously rotating carrier disc 22 carries the body along a curved path of travel through an ironing station F where the eyes A of the body are ironed out flat, as hereinbefore mentioned. This ironing out operation is effected by a pair of spaced and parallel, rotatable ironing elements or rollers 34, 35 (Figs. 1, 2 and 3) between which the mandrels 21 and the bodies B carried thereon, pass.

The ironing elements 34, 35 are horizontal and are disposed below and above the circular path of travel of the mandrels. These elements are formed on the inner ends of a pair of spaced and parallel actuating shafts 36, 37. The shaft 36 is journaled in a bearing 38 formed in a lower slide block 39 disposed in the lower portion of a vertical slideway 41 in a slide housing 42 bolted to the main frame 25. The outer end of the shaft extends through clearance slots 43 formed in the back of the slide housing and in the main frame.

The ironing roller shaft 37 is journaled in a bearing 45 formed in an upper slide block 46 disposed in the upper portion of the slideway 41. The outer end of this shaft 37 extends through clearance slots 47 formed in the back of the slide housing and in the main frame 25. Stop lugs 48 (Fig. 3) formed on the slide housing 42 and projecting inwardly from the slideway 41 keep the lower and upper slide blocks 39, 46 separated and confined in their respective portions of the slideway. These stop lugs align with the curved path of travel of the mandrels 21 through the ironing station F and thereby centralize the ironing rollers relative to the path of travel of the mandrels.

The two slide blocks 39, 46 are maintained under spring pressure against movement relative to each other, by a plurality of compression springs 51 which are carried on top of the upper slide block 46 and which distribute the pressure equally between the two blocks. There are four of these springs and they surround the upper ends of long bolts 52 which extend down through the two slide blocks and thus yieldably tie the blocks together. The lower ends of the bolts are formed with heads 53 (Fig. 1) which are anchored in the lower slide block 39 while the upper ends of the bolts are fitted with washers 54 and nuts

55 to adjust the spring pressure and to hold the springs in place.

The ironing rollers 34, 35 are rotated in unison and in time with the carrier disc 22 by a pair of meshing spur gears 58, 59 which are mounted on the respective actuating shafts 36, 37. Stop collars 61 are formed on the shafts intermediate their lengths. Spacer sleeves 62 surrounding the outer ends of the shafts adjacent the gears 58, 59 in cooperation with the stop collars, confine the shafts against endwise movement in their bearings during this rotation.

The gears 58, 59 are rotated by a pinion 65 which is mounted on the upper actuating shaft 15 37. This pinion meshes with and is driven by a large driving gear 66 which is carried on the main drive shaft 23. The relation between the pinion and the driving gear is such that the pinion makes one complete revolution each time the 20 driving gear rotates through a distance equal to the distance between the mandrels 21 on the carrier disc 22. This relation brings about a full turn of the ironing rollers 34, 35 for each mandrel 21 as the latter passes between the 25 rollers at the ironing station. The rollers rotate in opposite directions with their adjacent faces moving in the same direction as the mandrels moving along their path of travel, as shown by the indicating arrows in Fig. 1.

30 Hence as a mandrel 21 carries its non-rotating can body B between the rotating ironing rollers 34, 35 at the ironing station F, the rollers come into pressing engagement with the body at the areas which include the eyes or curved connecting parts A. This rolls out these eyes with a combined ironing and wiping action effective against the outside of the curved connecting parts. The two eyes engage the two rollers almost simultaneously and thereby prevent any turning of 35 the body on its mandrel. This ironing out action is progressive as the ironing rollers engage and roll against the non-rotating but moving body as it passes between them.

For the purpose of bringing about this progressive ironing action the outer peripheries of 45 the rollers are formed with a generated contour 68 which is proportioned to properly roll on the moving body as the body and the rollers come into and move out of engagement with each other. 50 This movement of the body and the rollers is graphically illustrated in Figs. 7 to 12, inclusive. By close examination of these views a clear conception of this generated rolling action will be obtained.

55 During this rolling action of the ironing rollers 34, 35 as the can body passes between them, the body on its mandrel forces the rollers apart slightly against the resistance of the springs 51 acting on the slide blocks 39, 46, the effect of the springs 60 completely equalizing pressure on the two sides of the mandrel. This prevents any offsetting strain on the mandrel during the ironing operation and thereby the parallelism of the rollers and the mandrel is not disturbed. This separating action increases the pressure of the rollers 65 against the curved connecting parts A at just the proper time and place to facilitate nullification thereof. The total separation of the rollers, however, is small and is not sufficient to unmash the 70 roller actuating gears 58, 59 or cause any interference in operation between the pinion 65 and the main driving gear 66.

With such a generated rolling action between the can body, backed up by its mandrel, and the 75 ironing rollers 34, 35 the curved connecting parts

A of the body are rolled out flat against the flats 31 on the mandrel and this flattening of the curved connecting parts sets the material beyond its elastic limit and thus effects a complete elimination of the curved connecting parts. The setting thus impressed on the eyes, springs the side walls of the body outwardly into their original rounded condition and completes the reforming of the body into the cross sectional shape shown in Fig. 6.

In this fully reformed condition the body D is slightly larger in diameter than the mandrel 21 on which it is supported. Hence the finished body may be readily stripped off the mandrel, manually or in any other suitable manner following which it may be removed to a suitable place of deposit.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In an ironing device for a machine for reforming collapsed partially opened can bodies having spaced apart side walls joined by opposed sharply curved connecting parts, the combination of a pair of oppositely disposed rotatable ironing elements, yieldable mountings for said elements to allow movement of the elements in a direction away from each other, a non-rotatable support movable along a path of travel between said ironing elements for supporting a can body with its curved parts in predetermined position, and means for moving said support in a continuous sweep along said path of travel to bring said body curved parts into passing momentary engagement with said elements, said yieldable element mounting insuring equal pressure on said opposed curved body parts to iron out said parts and thereby reform the can body to a desired shape.

2. In an ironing device for a machine for reforming collapsed partially opened can bodies having spaced apart side walls joined by opposed sharply curved connecting parts, the combination of a non-rotatable support movable along a predetermined path of travel for carrying a can body along said path of travel, means for moving said support and its can body along said path of travel, a pair of oppositely disposed rotatable ironing elements located one on each side of the path of travel of the can body carried by said moving support and between which said support passes, said ironing elements having generated contours, and means for rotating said ironing elements to progressively engage their contours with the areas of the can body adjacent said curved parts in a combined wiping and ironing action as the support passes between said elements for progressively ironing out said parts to reform the can body to a desired shape.

3. In an ironing device for a machine for reforming collapsed partially opened can bodies having spaced apart side walls joined by opposed sharply curved connecting parts, the combination of a non-rotatable support movable along a predetermined path of travel for carrying a can body along said path of travel, means for moving said support and its can body along said path of travel, a pair of oppositely disposed rotating iron-

ing rollers located one on each side of the path of travel of the can body carried on said support and between which said support passes for the engagement of the curved parts of the body with said elements to iron out said curved parts and thereby reform the can body to a desired shape, a pair of oppositely disposed slides in which said ironing elements are rotatably mounted, tie bolts extending through said slides for tying them together, compression springs on said tie bolts and acting against said slides equally for allowing equalized separation of said ironing elements during engagement of the elements with the curved parts of the body to exert pressure against the said parts equally during the ironing out operation and for maintaining parallelism between said elements and said support, and stop lugs disposed between said slides for centralizing the ironing elements relative to the support as it moves between said elements.

4. In an ironing device for a machine for reforming collapsed partially opened can bodies having spaced apart side walls joined by sharply curved connecting parts, the combination of a rotatable carrier disc, a non-rotatable support carried by said disc for transporting a can body along a circular path of travel with its two curved connecting parts in radial alignment, a pair of oppositely disposed rotatable ironing elements one located inside and one outside of said circular path, each ironing element having a generated contour, and means for rotating said ironing elements to progressively engage against said curved body parts during passage of the body between said ironing elements to keep the ironing elements in constant engagement with the body wall and to iron out said curved parts to reform the can body to a desired shape.

5. In an ironing device for a machine for reforming collapsed partially opened can bodies having spaced apart side walls joined by sharply curved connecting parts, the combination of a rotatable carrier disc, a plurality of non-rotatable supports carried by said disc for transporting can bodies along a circular path of travel with the two curved connecting parts of each body in radial alignment, a pair of oppositely disposed radially spaced slides located at one side of said disc, a rotatable ironing roller carried by each of said slides one roller being inside and one outside of said circular path, each of such rollers having a generated contour, pressure means acting against said slides to provide for yieldable separation of said ironing rollers, and means for rotating said ironing rollers during movement of said disc to bring the generated contours of the rollers against a passing can body to progressively press against said curved body parts during such passage, the yielding of said rollers equalizing the pressure against both of said curved body parts to iron them out and to reform the can body to a desired shape.

6. In an ironing device for a machine for reforming collapsed partially opened can bodies having spaced apart side walls joined by opposed sharply curved connecting parts, the combination of a pair of oppositely disposed spaced ironing elements yieldably mounted for movement toward and from each other, a support for a can body, oppositely disposed recessed surfaces in said support, and means for effecting continuous relative movement between said elements and said support to pass a can body on said support between said elements as the latter press said curved body parts against said recessed surfaces to iron

out the sharply curved connecting parts of the can body and thereby reform the can body to a desired shape.

7. In an ironing device for a machine for reforming collapsed partially opened can bodies having spaced apart side walls joined by opposed sharply curved connecting parts, the combination of a pair of oppositely disposed spaced ironing elements yieldably mounted for movement toward and from each other, a cylindrical can body support having oppositely disposed flats thereon for receiving the can body with the curved parts of the body adjacent said flats, and means for effecting continuous relative movement between said elements and said support to pass a can body on said support between said elements as the latter iron out the sharply curved connecting parts of the can body beyond their elastic limit against said flats and thereby reform the can body to a desired shape.

8. In an ironing device for a machine for reforming collapsed partially opened can bodies having spaced apart side walls joined by opposed sharply curved connecting parts, the combination of a pair of oppositely disposed spaced ironing elements, yieldable mountings for said elements to allow movement one from the other, a support movable in one direction along a path of travel between said ironing elements for supporting a can body, recesses in said support adjacent the sharply curved parts of a supported body, and means for moving said support in a continuous sweep along said path of travel for pressing engagement of the curved parts of the body against the walls of said recesses by said elements, said yieldable mountings insuring equalization of pressures upon said opposed curved body parts to iron out the parts and thereby reform the can body to a desired shape.

9. In an ironing device for a machine for reforming collapsed partially opened can bodies having spaced apart side walls joined by opposed sharply curved connecting parts, the combination of a pair of oppositely disposed rotatable ironing elements yieldably mounted for movement toward and from each other, a support having op-

posed recessed surfaces, said supports being movable along a path of travel between said ironing elements for supporting a can body with its curved parts adjacent said recessed surfaces, and means for moving said support in a continuous sweep along said path of travel for pressing engagement of the curved parts of the body between said elements and recessed support surfaces to iron out the parts and thereby reform the can body to a desired shape.

10. In an ironing device for a machine for reforming collapsed partially opened can bodies having spaced apart side walls joined by opposed sharply curved connecting parts, the combination of a pair of oppositely disposed rotatable ironing elements yieldably mounted for movement toward and from each other, a continuously rotatable carrier disc disposed adjacent said ironing elements, and a plurality of spaced and parallel, support mandrels secured in said disc, each of said mandrels having oppositely disposed axially elongated recessed surfaces, each mandrel being movable with the disc through a curved path of travel extending between said ironing elements for carrying a said can body with its sharply curved parts adjacent said recessed surfaces in a continuous sweep along said path of travel for momentary engagement of the curved parts of the body with said elements and recessed surfaces of the mandrel to iron out said curved parts and thereby reform the can body to a desired shape.
